COMBINED FINGERPRINTING AND FRAUD DETECTOR FOR CHECK IDENTIFICATION

Edward A. Essad, 1516 N. Hobart, Hollywood, Calif.

Filed Mar. 27, 1962, Ser. No. 69,456

Term of patent 14 years

(Cl. D52—1)

FIG. 1.

FIG. 4.

FIG. 2.

FIG. 5.

FIG. 3.

FIG. 6.

FIGURE 1 is a perspective view of a combined fingerprinting and fraud detector for check identification, showing my new design;

FIGURE 2 is a top plan view thereof;

FIGURE 3 is a front elevational view thereof;

FIGURE 4 is a bottom plan view thereof;

FIGURE 5 is a rear elevational view thereof; and,

FIGURE 6 is a side elevational view thereof, the opposite side having substantially an identical appearance.

I claim:

The ornamental design for a combined finger printing

and fraud detector for check identification, substantially as shown and described.
